ELECTRIC SWITCH

Thomas W. Thirlwell, Akron, Ohio

Application January 4, 1943, Serial No. 471,261

1 Claim. (Cl. 200—153)

My invention relates to electric circuits, and has among its objects and advantages the provision of an improved general purpose switch of the silent action type.

In the accompanying drawing:

Figure 1 is a face view of a wall plate such as is associated with a common wall outlet box illustrating my invention applied thereto.

Figure 2 is a sectional view along the line 2—2 of Figure 1.

Figure 3 is a sectional view along the line 3—3 of Figure 2 with the switch open.

Figure 4 is a similar view showing the switch in its closed position.

Figure 5 is a face view of the contacts and the switch actuating lever, and

Figure 6 is a sectional view along the line 6—6 of Figure 2.

In the embodiment of the invention selected for illustration, I make use of an ordinary wall outlet box 10 having flanges 12 to which is secured a strap 14 by screws 16. The wall plate 18 is attached to the strap 14 by screws 20. The switch structure 22 is mounted on the strap 14.

The switch structure 22 comprises a body 24 of insulative material. This body is recessed in one face, as at 26 to provide accommodation for a switch lever 28. This lever pivots about the axis of a pin 30, and the recess 26 is so shaped as to provide a three point contact with the lever, as at 32. The body 34 of the switch lever is flat and circular in contour throughout its greater extent and has one face lying against the bottom face of the recess 26. Shoulders 36 are formed on the switch body for selective engagement with shoulders 38 constituting wall areas of the recess 26. Thus the lever 28 is limited in its pivotal movement, as when shifted to off and on positions.

When viewed according to Figure 2, the outer face of the switch lever 28 lies flush with the body 24. A second body 40 of insulative material is attached to the body 24 by screws 42. A bowed spring 44 is housed in a groove 46 in the body 40 and has its apex engaging the switch lever 28 to frictionally bind the lever against the bottom face of the recess 26. The bottom face of the recess 26 is in the nature of a flange 48, since the body 24 is provided with an opening 50 to provide accommodation for a fixed contact strip 52 and a flexible contact strip 54. Durable points 56 and 58 are respectively attached to the strips 52 and 54.

Terminal screws 60 and 62 extend through the strips 52 and 54 and are threaded into the body 24 to clamp the strips against shoulders 64. A thin insulative plate 66 is attached to the body 24 by screws 68 for closing the opening 50.

One face of the switch lever 28 is recessed at 70, which recess includes an angular wall 72 arranged to engage the bend 74 in the spring strip 54 when the lever 28 is pivoted to one position, thereby bringing the contacts 56 and 58 into circuit closing engagement. In the position of Figure 3, the strip 54 lies loosely in the recess 70, but in the position of Figure 4, the strip bears against the side face of the switch lever to hold its contact 58 in firm engagement with the contact 56. The switch lever 28 is silent in operation and is easily moved from one position to the other. All the parts operate noiselessly.

20 In Figure 6, the pin 30 is supported in openings 76 in the bodies 24 and 40.

Two screws 78 attach the switch structure 22 to the strap 14, these screws being accessible through bores 80 in the body 24.

25 Openings 82 are provided in the strap 14 and the face plate 18 for accommodating the switch lever 28.

Without further elaboration, the foregoing will so fully explain my invention, that others may, by applying current knowledge, readily adapt the same for use under various conditions of service.

I claim:

In a switch, an insulated body having a recess therein, a lever pivoted in said recess for turning to on and off positions, said lever having a recess 35 in one side face thereof shaped to provide a camming surface inclined axially of the lever and in a direction concentric with the pivot, a fixed contact mounted on the body and spaced laterally of the recessed face of the lever, a resilient contact arm having one end fixed to the body and extending transversely of the lever, said arm being bent longitudinally to offset its other end transversely with relation to its fixed end

40 so that said other end of the arm is biased into the recess of the lever when the latter is in off position, and a contact carried by said other end of the arm movable into engagement with the fixed contact by engagement of the arm with the camming surface of the lever when the latter is turned to on position.

THOMAS W. THIRLWELL.
